(57) **CLAIM**

The ornamental design for a motor vehicle and/or toy replica thereof, as shown and described.

DESCRIPTION

FIG. 1 is a front left perspective view for a motor vehicle and/or toy replica showing our new design;

FIG. 2 is a rear left perspective view thereof;

FIG. 3 is a front view thereof;

FIG. 4 is a rear view thereof;

FIG. 5 is right side view thereof;

FIG. 6 is a left side view thereof; and,

FIG. 7 is a top view thereof.

The bottom view of the motor vehicle and/or toy replica forms no part of the claimed design.

1 Claim, 7 Drawing Sheets
